COMPRESSOR

Keith H. Rhodes, Racine, Wis., assignor to Walker Manufacturing Company, Racine, Wis., a corporation of Delaware

Filed Sept. 6, 1962, Ser. No. 221,729
1 Claim. (Cl. 230—172)

This invention relates generally to air compressors and more particularly to an improved positive displacement air compressor.

Conventional positive displacement air compressors generally comprise a piston that is driven by a crank-shaft through an articulated connecting rod. The piston is movable in translation within a complementary cylinder, eccentricity of the crankshaft being accommodated by articulation of the connecting rod.

The air compressor of the instant invention features a one-piece piston and connecting rod that is molded from nylon or similar material, thereby eliminating the conventional connecting rod and wrist pin, as well as the problems attendant to manufacture and assembly of the rod, wrist pin and piston.

Accordingly, one object of the instant invention is an improved air compressor.

Another object of the instant invention is an air compressor having a one-piece piston and connecting rod.

Another object of the instant invention is an air compressor having a piston molded from nylon or similar material.

Another object is an air compressor that eliminates the conventional wrist pin and connecting rod assembly.

Another object is an improved balancing system for an air compressor.

Other objects and advantages of the instant invention will be apparent in the following specifications, claims and drawings, wherein:

FIGURE 1 is a side view of an air compressor in accordance with an exemplary embodiment of the instant invention shown in operative association with a conventional electric motor;

FIG. 2 is a cross sectional view taken substantially along the line 2—2 of FIGURE 1;

FIG. 3 is a cross sectional view taken substantially along the line 3—3 of FIG. 2;

FIG. 4 is a view taken substantially in the direction of the arrow 4 in FIG. 2 with the crankshaft rotated approximately 90°;

FIG. 5 is a cross sectional view similar to FIG. 2 of a modified form of the air compressor of the instant invention; and

FIG. 6 is a cross sectional view taken substantially along the line 6—6 of FIG. 5.

As best seen in FIGURE 1 of the drawings, an air compressor 10, in accordance with an exemplary embodiment of the instant invention is shown in operative association with an electric motor 12. The air compressor 10 is secured to the motor 12 as by a pair of mounting bolts 14 and 16 (FIG. 2) having complementary nuts 18 and 20, respectively.

As best seen in FIG. 2 of the drawings, the air compressor 10 comprises a crank housing 20, preferably a steel stamping, having a pair of radially extending flanges 22 and 24 with apertures 26 and 28 for the acceptance of the mounting bolts 14 and 16 on the motor 12, respectively. The housing 20 is of tubular construction having an inside diameter complementary to a bearing housing 30 of the motor 12 for the acceptance thereof in slidably press fit relationship.

The crank housing 20 has an inner end plate 32 with an outer peripheral rib portion 34 of a diameter comple-

2

mentary to the inside diameter of the housing 20 so as to be acceptable therein in press fit relationship. The end cap 32 has an aperture 36 therein for the acceptance of an output shaft 38 of the motor 12. The housing 20 also has an annular outer end cap 40 with a peripheral rib 42 thereon of a diameter complementary to the inside diameter of the housing 20 so as to be acceptable therein to press fit relationship. The outer end cap 40 is of annular construction for the acceptance of a complementary circular valve assembly generally designated by the numeral 50, the details of which will be described hereinafter.

A cylinder 60, of circular cross section, is secured within a complementary aperture 62 in the housing 20, as by brazing. The cylinder 60 has an inside diameter similar to the inside diameter of the annular end cap 40 for the acceptance of a valve assembly 50 of identical construction to the valve assembly 50 in the end cap 40 of the housing 20.

A piston 70, molded from, for example, nylon or a fluorocarbon, functions as a combined piston, wrist pin and connecting rod. A cylinder-contacting peripheral surface 72 on the piston 70 is defined by what may be termed a section of a sphere. Thus, whatever the angularity of the piston 70 relative to the central axis of the cylinder 60, the surface 72 is maintained in sealing line contact with the cylinder 60. An end portion 74 of the piston 70 has a bore 76 therein for the acceptance of a crank pin 78. It is to be noted that the crank pin 78 is secured directly to the output shaft 38 of the motor 12 by a machine screw 80, a threaded end portion 82 of which is accepted in a complementary threaded bore 84 in the crank pin 78. It is also to be noted that a head portion 86 of the machine screw 80 is of relatively large diameter and axial dimension, thereby to function, in combination with a counterweight cup 90, as a counterweight for the crank pin 78, thereby to statically balance the crank pin 78 and the piston assembly 70.

As best seen in FIGS. 2 and 3, the valve assembly 50 comprises a tubular valve housing 100 having a pair of diametrically related flanges 102 and 104 thereon to facilitate attachment of the housing 100 to an annular valve plate 106. The valve plate 106 is retained on the cylinder 60 by a plurality of folded tabs 107, 108 and 109 thereon.

A sleeve 110 is disposed interiorly of the valve housing 100 to function as a stop for a generally rectangular disc valve 112. The disc valve 112 is seated alternatively against the valve plate 106 to close a central aperture 113 therein and against an annular end portion 114 of the sleeve 110, as will be described. The sleeve 110 has a plurality of circumferentially spaced apertures 116 therein for the passage of air outwardly of the valve housing 100 when the valve 112 is seated against the seat 114 on the sleeve 110.

An annular flapper valve 120 having a central aperture 121 is retained against the valve plate 106 by a pair of rivets 122 and 124 that extend through complementary spacers 126 and 128, respectively. The flapper valve 120 normally closes a pair of apertures 130 and 132 (FIGS. 1 and 3) in the valve plate 106 to preclude the passage of air outwardly therethrough.

Upon movement of the piston 70 downwardly, as seen in FIG. 2 of the drawings, the flapper valve 120 deflects downwardly, as seen in FIG. 3 of the drawings, due to a pressure differential created thereacross, whereupon air is admitted through the apertures 130 and 132 in the valve plate 106.

Upon movement of the piston 70 upwardly within the cylinder 60, as seen in FIG. 2 of the drawings, the flapper valve 120 is biased against the valve plate 106 by the air pressure differential thereacross and by its own resilience, sealing the apertures 130 and 132 in the valve plate 106.

The disc valve 112 is biased against the edge portion 114 on the sleeve 110, thereby permitting discharge of air under pressure outwardly through the central apertures 121 and 113 in the flapper valve 120 and valve plate 106, respectively, around the disc valve 112, through the apertures 116 in the sleeve 110 and outwardly of the valve housing 100.

It should be apparent that the use of valve assemblies 50 on opposite sides of the piston 70 results in a double action air compression in that air is compressed upon movement of the piston 70 in either direction.

As seen in FIG. 5 of the drawings, a modified air compressor 200 comprises a crank housing 202 having radially extending flanges 204 and 206 to facilitate attachment of the air compressor 200 to the motor 12. A cylinder 210 is secured to the housing 202 as by brazing. The cylinder 210 is provided with a pair of valve assemblies 50 similar to the valve assemblies discussed hereinbefore, which are supported in axial alignment with the central axis of the cylinder 210 and normally to the central axis 38 of the motor 12.

From the foregoing description, it should be apparent that the air compressors 10 and 200 feature a piston which is molded of nylon or similar material. The piston is unique in that it combines the customary piston, wrist pin and connecting rod of conventional piston-type compressors heretofore known and used. The cylinder-contacting surface of the piston comprises a center section of a sphere. Thus, sealing line contact is maintained between the piston and the cylinder wall independently of the angularity of the rod portion of the piston. The compressor housing and cylinder assembly are made up from simple relatively light gauge steel components.

Standard valve assemblies are utilized on opposite sides of the piston to effect compression of a working fluid on each stroke of the piston. The crank pin is secured directly to the output shaft of the motor and is retained in this position by a machine screw that also functions as a counterweight.

It is to be understood that the specific constructions of the improved compressor herein disclosed and described are presented for the purpose of explanation and illustration and are not intended to indicate limits of the invention, the scope of which is defined by the following claim.

What is claimed is:

A positive displacement piston-type air compressor for attachment directly to a rotatable shaft, said compressor comprising a cylinder, a one-piece molded plastic piston in said cylinder, said piston having a spherical head portion at one end thereof and a bore in an opposite end portion thereof extending transversely to the central axis of said cylinder and parallel to the central axis of said rotatable shaft in abutting parallel relationship, a cylindrical crank pin having one end portion secured directly to said rotatable shaft whereby the central axis of said crank pin is radially spaced from the central axis of the shaft, the other end of said crank pin being journaled directly in the bore in the opposite end portion of said piston, and an intake and an exhaust valve in said cylinder whereby rotation of said shaft effects reciprocation and articulation of said piston and induction and compression of air in said cylinder.
